naled the pinch rolls 3, said second set overlying said rolls 3 and being adapted for directing short lengths of sheet bars fed therethrough to a bar piler, generally designated by the reference character D, which is of any ordinary or preferred construction and which is located directly over the boshing tank 1 or over the transfer table B' according as one or the other is employed.

10 The driving means for the conveyors of the cooling bed comprises a power mechanism whereby intermittent rotary movement is imparted to the shaft 18 for advancing the conveyors step by step, and also includes means whereby said power mechanism is actuated by passage of sheet bars to their proper position on the transfer table in readiness to be shifted to the cooling bed.

Said power mechanism comprises a shaft 20 36 which is suitably coupled, as by a coupling 36^a to the shaft 18 of the cooling bed mechanism and which carries thereon a ratchet wheel 37. Mounted for independent rotary movement upon the shaft 36 adjacent to said 25 ratchet wheel is an arm 38 of approximately triangular form, and pivoted to said arm at the forward outer angle thereof is a pawl 39 which rides upon the periphery of said ratchet wheel and which is adapted to engage with a tooth of the latter for imparting thereto a partial rotation when said arm is actuated to swing forward on said shaft 36. The rear outer angle portion of said 30 arm 38 is pivotally attached to the upper end of a connecting rod 40 which has its lower end pivoted to a piston 41 which is arranged for reciprocation within an upright air, hydraulic, or steam cylinder 42 which has its upper end open. The extreme 35 lower end of said cylinder communicates through a side-opening port 43 with a second, or auxiliary, cylinder 44 in which is disposed a vertically reciprocable piston 45. Said piston 45 is carried on the lower end of a piston rod 46 which extends outward through the upper end of the cylinder 44 and which is connected by a pivoted link 47 to the lower end of the movable core 48 of a suitable electromagnet 49. Said elec-

50 tronagnet is normally maintained deenergized, as will hereinafter be explained, causing said core 48 to occupy its lowered position in which the piston 45 is located at the limit of its downward movement. When, 55 however, said electromagnet is energized, the core 48 is instantly elevated, lifting the piston 45 to a point wherein the port 43 is thereby uncovered. The pressure fluid which enters said cylinder 44 through a port 60 50 in the lower end of the latter is thus permitted to enter the cylinder 42 for effecting upward reciprocating movement of the piston 41 whereby, through the intermediacy of the connecting rod 40, arm 38, pawl 39 65 and ratchet 37, a partial rotary movement

of the shaft 18 is produced for advancing the conveyor mechanism of the cooling bed throughout a single step of definite length.

As said piston 41 approaches the limit of its upward movement, a seat portion 41^a 70 formed on its upper end engages an anti-friction roller 51 carried by the adjacent end of a lever 52 which is pivoted intermediate its ends upon the upper end of a link-like rocker arm 53 that has its lower 75 end mounted upon a fixed part of a suitable frame structure 55 with which the described parts of the driving mechanism are associated. The opposite end of said lever 52 is pivoted to the link 47. Thus, in the final 80 portion of the upward movement of said piston 41, the lever 52 is swung on its mounting whereby the piston 45 is positively thrust downward to its normal seated position, the core 48 of the electromagnet having been previously released through the breaking of the energizing electric circuit in which said electromagnet is located, as will hereinafter be explained. The return of 85 said piston 45 cuts off the entrance to the cylinder 42 of the actuating fluid through the port 43 and opens said port for the exhaust therethrough of the spent fluid, said piston having intermediate its ends a reduced portion or annular channel 54 which 90 provides for free communication around said piston between said port 43 and an exhaust port 56 leading to the atmosphere 95 through the wall of the cylinder 44.

As the spent pressure fluid exhausts from the cylinder 42, the piston 41 is returned to its normal position by pressure fluid admitted to the upper end of a relatively small cylinder 57 which is located in a suitable position above said cylinder 42 and which has 100 operating therein a piston 58 connected by a connecting rod 59 to the upper end of the connecting rod 40. As is manifest, the downward movement of said pistons 41 and 58 effects retraction of the pawl 39 throughout the distance required to position it in engagement with the next tooth of the ratchet 37.

The cylinder 57 is made of such relatively 105 smaller size than the cylinder 42 that, while it suffices to return the piston 41 to its lowered position upon the release or exhaust of the pressure, or motive, fluid from said cylinder 42, the downwardly directed force of the fluid supplied thereto is insufficient 110 to unduly retard upward movement of the piston 41 under the motive force admitted to said cylinder 42.

The electromagnet 49 is located in an electric circuit which includes a circuit closer 115 adapted to momentarily effect closing of the circuit at predetermined times. As shown in Fig. 13 for illustrative purposes, said circuit closer comprises a movable contact 60 carried by the upper end of arm or bar 61 120

WILLIAM J. TALLMAN AND CHARLES J. BACON, OF BUFFALO, NEW YORK, ASSIGNEES
TO DUPONT FIBERSILK COMPANY, OF TONAWANDA, NEW YORK.

DRUM FOR SPINNING MACHINES.

Application filed January 17, 1924. Serial No. 686,724.

To all whom it may concern:

Be it known that we, WILLIAM J. TALLMAN and CHARLES J. BACON, citizens of the United States, residing at Buffalo, in the county of Erie and State of New York, have invented a new and useful Improvement in Drums for Spinning Machines, of which the following is a specification.

This invention relates to drums of the kind used in connection with the manufacture of artificial silk.

It has been found desirable to use drums of this kind having a cylindrical surface made of glass for the reason that the fibers of artificial silk adhere well to a glass surface and for the reason that glass has the property of withstanding the chemical action of the acid solutions to which the drums are subjected while in use.

Drums heretofore used were made entirely of glass and since these drums must be handled frequently during the process of manufacture of artificial silk and must be subjected to different temperatures during different parts of the process, considerable difficulty has been experienced in the use of these glass drums due to breakage. Much of this breakage occurs at the ends of the drums, and since employees must handle the drums at the end portions thereof, injuries are frequently received by employees, which injuries are often aggravated by the presence of acids on the drums.

The objects of this invention are to provide drums which can be used in place of the single piece glass drums heretofore used and which are so constructed as to resist the breaking of the drums; also to produce drums of this kind which are of more durable and rugged construction than drums heretofore used and which require less careful handling by operatives; also to improve the construction of drums of this kind in other respects hereinafter specified.

In the accompanying drawings:

Fig. 1 is an elevation of a drum embodying this invention.

Fig. 2 is a transverse section thereof on line 2—2, Fig. 1.

Fig. 3 is a longitudinal central section thereof.

Fig. 4 is an elevation of a drum of modified construction.

Fig. 5 is a longitudinal central section thereof.

Fig. 6 is a longitudinal central sectional elevation of a drum of slightly different construction.

Fig. 7 is a sectional elevation thereof on line 7—7, Fig. 6.

In the construction shown in Figs. 1 to 3, A represents a hollow, open-ended glass cylinder having a smooth exterior upon which the silk fibers are wound during the process of manufacture and on the ends of which metal end pieces may be secured. In the particular construction shown in Figs. 1-3, these end pieces are secured to the glass cylinder by means of external threads *a* formed on the outer ends of the cylinder. B represents the end pieces which may be made of any suitable material which is not readily breakable and which is adapted to withstand the action of the acids or vapors to which the drums are subjected, aluminum, for example, having been found to be well adapted for this purpose. Other metals, however, may be used, and, if necessary, they may be plated or covered with metals or materials resisting the action of acids. Each of the end pieces B is provided with an outer flange portion *b* having an internally threaded part *b'* adapted to engage with the threads *a* of the glass cylinder. The flange *b* extends laterally from a body portion *b*² of the end piece, which extends substantially radially with reference to the axis of the cylinder. The radial body portion is provided with an annular depression *b*³ at the inner face thereof adjacent to the flange *b* and a gasket *b*⁴ of resilient or flexible material may be inserted into the depression to cooperate with the end of the glass cylinder for the purpose of forming a secure joint therewith, and also for forming a liquid-tight packing to prevent liquid from flowing into the interior of the cylinder. The gasket also forms a cushion which serves to absorb shocks to which the end piece may be subjected and thereby decreases the tendency of the cylinder to break. The elasticity of the gasket also tends to cause the threads of the end pieces to yieldingly grip the threads of the cylinder and thus prevents accidental unscrewing of the end pieces from the glass cylinder. The radial body portion of each end piece terminates in an outwardly projecting flange or part C upon which the drum may be supported when standing on end. The outer face of

the threaded flange b preferably converges axially from the radial body portion b^2 , forming a raised portion D at the outer periphery of the body portion which may co-operate with the usual rubber rollers for rotating the drum during the process of manufacturing artificial silk.

In the construction shown in Figs. 4 and 5, a glass cylinder E is used which differs 10 from the cylinder A in that it is provided with internal threads e , the entire outer face of the cylinder E being smooth and consequently available for winding artificial silk thereon. The end pieces, in this construction, are each provided with a substantially radial body portion F having an annular flange f adapted to extend into the glass cylinder and having threads f' adapted to engage the threads e of the cylinder. The 15 body portion of the end piece extends outwardly beyond the outer periphery of the glass drum, as shown at g' , and serves the two-fold purpose of confining the silk upon the glass drum, and of engaging with the 20 usual driven rubber rollers (not shown) which are used during a part of the process of manufacturing artificial silk, to impart rotary motion to the drum. f^2 represents 25 reinforcing ribs which may be arranged at intervals connecting the inwardly extending flange f with the radially extending body portion F of the end piece. The outwardly extending part of the body portion is also provided with an annular groove g^2 arranged 30 adjacent to the threaded portions of the inwardly extending flange and containing a flexible gasket similar to the gasket 35 shown in Figs. 1-3.

In the construction shown in Figs. 6 and 40 7, a plain glass cylinder H is employed, and the end pieces I are held in place thereon by means of the tie bolts or rods K which extend through holes in one of the end pieces and engage in threaded holes in the opposite 45 end piece. Preferably two of the bolts or rods have a threaded engagement with one of the end pieces and the two other bolts extend through the cylinder in the opposite direction and engage with threaded holes in 50 the other end piece. In order to correctly center the glass cylinder and end pieces relatively to each other, the end pieces are preferably provided with inwardly extending, annular shoulders i and an annular shouldered gasket or packing ring L of flexible 55 material is interposed between the glass cylinder and each end piece, the shoulder of the gasket fitting between the shoulder of the end piece and the inner surface of the end 60 of the cylinder. Thus, the shoulders of the end pieces center the cylinder with reference to the end pieces and also serve to securely hold the end pieces against lateral displacement on the ends of the cylinder.

65 Drums of the kind described have the ad-

vantages that the metal end pieces greatly reduce the chances of breakage due to the fact that the metal ends protect the glass cylinders against endwise blows or shocks, and the fact that the peripheral portions of the end pieces extend beyond the periphery of the glass cylinder also to a large extent protects the glass against lateral blows or shocks. The protective end pieces are not subject to splitting or cracking as are glass 70 ends and consequently employees cannot cut 75 their hands in the handling of our improved drums, even if a break should occur in the glass cylinder. By reducing the chances of breakage of the drums, the losses due to injury of employees and damage of goods on the drums are greatly reduced, and by providing a drum of this kind of more rugged construction, the employees need not exercise the same care in handling the drums, so 80 that greater efficiency in the manufacture of 85 artificial silk results. In case a cylinder should be broken, the end pieces may be used again on another cylinder, so that the expense of replacing broken cylinders is much 90 less than in constructions heretofore used.

It will, of course, be understood that it is not intended to limit this invention to the particular constructions shown, since end pieces of other construction may be provided and the means for holding the end pieces on the glass cylinders may also be varied. The end pieces, while preferably made of metal, may be made of other materials which resist breakage, such, for example, as 95 hard rubber compounds or the like. It is also not intended to limit the invention to use in connection with cylinders made of glass, and the word "glass" as used in this 100 description and in the claims, is intended to 105 include frangible materials other than glass and which may be used in connection with the manufacture of artificial fibers.

We claim as our invention:

1. A spinning machine drum for use in 110 the manufacture of artificial silk or the like, including a hollow, open-ended glass cylinder, and protective end pieces made of material which is not readily broken and held on the open ends of said cylinder and having parts extending radially beyond the periphery of said cylinder, and parts extending axially beyond the ends of said cylinder and upon which said drum may be supported in 115 upright positions.

2. A spinning machine drum for use in the 120 manufacture of artificial silk or the like, including a hollow, open-ended glass cylinder having threads formed thereon adjacent to the ends thereof, and protective end pieces having parts adapted to engage said threads for securing said end pieces to said cylinder and axially extending parts adapted to support the drum in upright positions.

3. A spinning machine drum for use in the 130

manufacture of artificial silk or the like, including a hollow, open-ended glass cylinder, and protective end pieces, said cylinder and end pieces having cooperating parts 5 for securing said end pieces to said cylinder, said end pieces having parts extending radially beyond the periphery of said glass drum to protect said drum against damage, and parts on which said drum may rest when 10 in an upright position.

4. A spinning machine drum for use in the manufacture of artificial silk or the like, including a hollow, open-ended glass cylinder having threads formed thereon adjacent 15 to the ends thereof, and protective end pieces having substantially radially extending body portions extending beyond the periphery of said glass cylinder and parts extending laterally in opposite directions, one of 20 said parts of each end piece being adapted to engage the thread of one end of said cylinder and the other part forming a rest upon which the drum may be supported when standing in an upright position.

5. A spinning machine drum for use in the manufacture of artificial silk or the like, including a hollow, open-ended glass cylinder, protective end pieces made of material which 25 is not readily broken and which are held on

the open ends of said cylinder and have 30 parts extending radially beyond the periphery of said cylinder and parts extending axially beyond the ends of said cylinder and upon which said drum may be supported in upright positions, and gaskets of flexible 35 material interposed between said cylinder and said end pieces.

6. A spinning machine drum for use in the manufacture of artificial silk or the like, including a hollow, open-ended glass cylinder having threads formed thereon adjacent to the ends thereof, and metal end pieces having substantially radially extending body portions extending beyond the periphery of said glass cylinder and parts extending 40 laterally in opposite directions, one of said parts of each end piece being adapted to engage the thread of one end of said cylinder and the other part forming a rest upon which the drum may be supported when 45 standing in an upright position, and gaskets of resilient material interposed between said cylinder and said end pieces and adapted to form a seal between said cylinder and said end pieces and to absorb shocks to which 50 said end pieces may be subjected.

WILLIAM J. TALLMAN.
CHARLES J. BACON.
